UNITED STATES PATENT OFFICE.

WILLIAM G. LUTTINGER, OF JEROME, ARIZONA.

SAFETY-STIRRUP.

1,321,653.

Specification of Letters Patent. Patented Nov. 11, 1919.

Application filed April 23, 1919. Serial No. 292,039.

To all whom it may concern:

Be it known that I, WILLIAM G. LUTTINGER, citizen of the United States, residing at Jerome, in the county of Yavapai and 5 State of Arizona, have invented certain new and useful Improvements in Safety - Stirrups, of which the following is a specification.

This invention relates to stirrups and 10 more particularly to a safety stirrup.

The primary object of this invention resides in the provision of a stirrup whereby the possibility of dragging the rider of a horse will be eliminated should he be thrown 15 from the saddle.

A further object of this invention resides in the provision of a stirrup having a coacting multiplicity of elements that readily perform the functions of the common stirrup under normal riding conditions, the 20 same being susceptible to separation should the rider be accidentally thrown from the saddle.

With these and other objects in view this 25 invention resides in certain novel features of construction and combination of coacting elements which will be fully set forth in the specification, illustrated in the drawing and pointed out in the appended claims, it being 30 understood that certain changes in detail may be resorted to as come within the scope of the appended claims.

In the accompanying drawing:

Figure 1 is a side view of a stirrup constructed in accordance with this invention with the foot rest thereof shown in full lines in its normal position and in dotted lines in an upset position;

Fig. 2 is a vertical sectional view on the 40 line 2-2 of Fig. 1 with the foot rest shown in dot and dash lines;

Fig. 3 is a detail sectional view of the foot rest trunnion and a portion of the stirrup hanger.

Referring more particularly to the present embodiment of this invention the numeral 5 designates the strap engaging sleeve of the stirrup 6. This strap engaging sleeve has an aperture therethrough for the reception 50 of a pin 7 or the like in order that hangers 8 can be pivotally supported at opposite ends of the sleeve. Integrally formed on the central portion of said sleeve is a downwardly projecting keeper 9 in the lower surface of 55 which is provided a groove 10 for a purpose to be hereinafter set forth.

The aforesaid hangers are formed from any suitable material but in this instance they are made from a resilient metal that is bent outwardly to provide sufficient space 60 therebetween for bending their end portions upon themselves to provide upwardly directed resilient arms 11. These arms are provided as at 12 with apertures which are intersected by vertically disposed grooves 13 65 that gradually incline outwardly from their points of intersection.

Supported by the arms 11 is a substantially rectangular frame which forms what will be hereinafter referred to as a foot rest 70 14. Permanently secured to the sides of this foot rest are trunnions 15 which have their outer ends beveled so that their lower outer edges will be in advance of the upper outer edges for engaging the aforesaid apertures in the arms 11. With the outer ends of the trunnions so beveled, the upper edges thereof will be permitted to wedge the resilient arms 11 apart after an abnormal strain on the stirrup has caused the lug 16 80 carried by the foot rest to disengage its keeper 9; thus it is apparent that as the trunnions rotate and slide downwardly, the arms 11 will yield and as soon as the said trunnions are beyond the grooves the foot 85 rest will free itself from the hangers.

With this invention as herein set forth it is manifest that a stirrup is produced which is cheap of manufacture, efficient in performing its functions and neat in appearance. 90

Thus having fully described this invention what I claim is:

1. In a stirrup of the character described, the combination of a sleeve, hangers supported thereby, resilient upturned arms on said 95 hangers having oppositely disposed apertures therein intersected by vertically disposed grooves, a foot rest, trunnions on said foot rest with their outer lower edges seated in said apertures and their outer upper edges terminating at the bases of said grooves, a keeper on said sleeve with a groove in its lower surface, and a lug on said foot normally resting in said groove in said keeper. 100

2. A stirrup of the class described comprising a pair of spaced hangers having their lower end portions returned to afford spring arms, said arms being provided with openings, a foot rest provided with trunnions seated within the apertures of the 110 arms, said trunnions having their outer ends beveled, and means for normally holding

the foot rest against rotation about its trunnions.

3. A stirrup of the class described comprising a pair of spaced hangers having 5 their lower end portions returned to afford spring arms, said arms being provided with openings, a foot rest provided with trunnions seated within the apertures of the arms, said trunnions having their outer ends 10 beveled, and means for normally holding the foot rest against rotation about its trunnions, the inner faces of the arms being provided with longitudinally disposed grooves intersecting the apertures therein.

15 4. A stirrup of the class described comprising a pair of spaced hangers having

their lower end portions returned to afford spring arms, said arms being provided with openings, a foot rest provided with trunnions seated within the apertures of the 20 arms, said trunnions having their outer ends beveled, and means for normally holding the foot rest against rotation about its trunnions, the outer faces of the arms being provided with longitudinally disposed grooves 25 intersecting the apertures therein, each of said grooves at opposite sides of the aperture having its base portions inclined toward the aperture.

In testimony whereof I affix my signature. 30

WILLIAM G. LUTTINGER.
